UNITED STATES PATENT OFFICE.

JOHN HAMILTON, OF ST. JOHNS, NEW BRUNSWICK, CANADA.

MACHINE FOR DRESSING SHIPS' SIDES.

SPECIFICATION forming part of Letters Patent No. 299,639, dated June 3, 1884.

Application filed October 20, 1883. (No model.)

To all whom it may concern:

Be it known that I, JOHN HAMILTON, of St. Johns, New Brunswick, Dominion of Canada, have invented a new and Improved Machine for Dubbing and Planing the Sides of Vessels, of which the following is a full, clear, and exact description.

My invention consists of a contrivance of machinery whereby a rotary cutter or planer 10 may be applied to and operated upon the sides of vessels to dub the same, by means of a crank-shaft to be operated by hand; or power may be applied, if preferred, so as to dub and plane the sides of vessels better, faster, and with less 15 labor than by the ordinary methods of dubbing and planing by hand-tools, as hereinafter fully described.

Reference is to be had to the accompanying drawings, forming part of this specification, 20 in which similar letters of reference indicate corresponding parts in all the figures.

Figure 1 is a side elevation of my improved dubbing and planing machine applied to the side of the ship for use, with some parts in 25 section; and Fig. 2 is a cross-sectional view of the machine on line $x x$, Fig. 1, looking upward, and with some of the parts in section.

I mount a beam, a , that carries the cutter and its driving-gear, in two curved and slot- 30 ted supports, b , so as to be shifted along said supports by the blocks c , arranged in the slots or ways of said supports, and by the screws d , connecting the ends of said beam to said blocks, with nuts e and washers f , to bind the 35 frame fast at any position in the supports, as the beam is to be shifted from time to time by swinging it as on a pivot at the center between the supports b to set the cutting-tool or planer for successive operations. The supports b , 40 which are a little less than semicircles, are connected together at the ends by the bars g , and they have guide-lugs h at said ends, by which they are fitted in the grooves of a pair of guide-timbers, i , that are connected to the 45 ship's side j by bolts and nuts k , with temper-screws l between said bolts, by which the guide-timbers are adjusted parallel with the sides of the ship, so that the planing-tool carried on the beam a will be properly gaged to

the side of the ship, both when the frame is 50 shifted up and down the side of the ship in the supports b , and when it is shoved along the side of the ship by moving supports b along the grooved timbers i .

A rotary planer-tool, m , of suitable form to 55 dress the sides of the ship true and smooth is mounted on the end of the arbor n , fitted in suitable bearings in the beam a to be revolved, and also to be shifted lengthwise by an extensible device of the arbor, to set the cutter according to the depth it is desired the tool shall cut, the arbor being connected at its other end with an adjusting-screw, o , fitted in a bracket, p , and said arbor being also geared by a pinion, q , with a train of driving-gears 60 to be operated by the crank-shaft s , and said pinion q being fitted to the arbor so as to allow said arbor to be shifted through it for adjusting the cutter, as above stated. The frame a is also pivoted on the bolts d , connecting it 65 to the blocks c , and is made to swing or cant, so as to be always parallel with the part of the ship operated on, by an adjusting-screw, t , or it may be a lever, said screw t being fitted in a bracket, u , of one of the blocks c and 70 arranged to turn the frame more or less on the bolts d , to adjust the tool to the surface of the vessel's side to be planed.

It will be seen that the supports b will traverse the guide-timbers i when they are sprung 80 to the curvature of the ship without binding by means of the guide-lugs h , to carry the dubbing and planing-tool along the curved sides of the ship; also, that the tool can be swung up and down the side of the ship, parallel to it, by 85 oscillating it in the supports b , and the tool can be set parallel to any part of the varying form of the ship's side by the screw t , and can be shifted by the adjusting-screw o to reach the surface and to regulate the cutting of the 90 same, so that all or nearly all parts of the sides of the ship may be dressed with much less labor than in the common way. The machine is to be operated by two men, one of which will turn the crank to give motion to 95 the cutting-tool, while the other shifts the machine along the ways i and up and down the supports b .

It may be preferable in some cases to connect the ends of supports *b* with the bars *g* by slack joints, to facilitate the shifting of the supports along the guides *i*, by twisting at the joints, when it may occur that one will have to be sprung more than another to conform with different curves of the side of the ship. This may be done by fitting bolts *v* slack in the bars *g*. The machine is to be used inside or outside of the ship, and is to be fitted with different forms of cutters adapted for plank or timber. A balance-wheel will be fitted in the cutter-arbor at any suitable place, to facilitate steady motion of the cutters.

15 Along the sides of the vessel where it is comparatively straight the guides *i* can be as long as may be convenient; but around the bow and under the center and run at the stern, where the curves are quicker, the length of the guides may be limited.

15 It is to be observed that the beam *a* is to be set firmly in the supports *b* by the screws *d* and nuts *e*, while the machine is being shoved along the guides for making the cut. The screws 25 are then to be slackened to shift the cutter up or down for another cut, and then the beam is set again until the whole space between the guides *i* is dressed. The guides are then shifted to a new position on the side of the ship, and 30 so on.

It is designed to construct the machine in suitable size to dress a space about three feet wide between the guides *i*, but of course it may be larger or smaller, as preferred.

35 Having thus described my invention, I claim as new and desire to secure by Letters Patent—

1. The combination, in a dubbing and planing machine, of a beam, *a*, having a cutter and driving-gear mounted on it, curved supports 40 *b*, in which said beam is adjustably mounted, and guides *i*, attached to the ship's side and having the supports *b*, arranged to be shifted along them, substantially as described.

2. The beam *a*, having the cutter and driving-gear mounted on it, in combination with 45

curved supports *b*, arranged in the guides *i*, the beam *a* being connected to the supports *b* by the blocks *c* and bolts *d*, the blocks being adjustable along the supports, and the bolts being arranged to clamp the beam fast to the 50 supports, substantially as described.

3. The beam *a*, having the cutter and driving-gear mounted on it, in combination with the supports *b*, arranged in guides *i*, the beam being connected to supports *b* by clamping and 55 pivot bolts *d*, whereon the beam is adjustable to adjust the cutter to the surface of the ship's side, substantially as described.

4. The beam *a*, having the cutter and driving-gear mounted on it, in combination with 60 the supports *b*, arranged in the guides *i*, and being pivoted on the connecting-bolts *d*, and having an adjusting screw, *t*, to set it on said pivot-bolts, substantially as described.

5. The beam *a*, having the cutter and driving-gear mounted on it, in combination with the supports *b*, arranged in the guides *i*, the cutter *m* being adjustable to and from the beam by an extensible arbor, to adjust it to the work and to regulate the depth of the cutting, 70 substantially as described.

6. The beam *a*, having the cutter and driving-gear mounted on it, in combination with the supports *b* and guides *i*, and being adjustable on its pivot-supports *d*, and the cutter being arranged on an extensible arbor, substantially as described. 75

7. The combination, with guides *i*, attached to the sides of the ship by bolts *k*, and temper-screws *l*, for springing them to the curves of 80 the ship, of the beam *a*, having a cutter and driving-gear mounted on it, and the supports *b* for said beam, said supports *b* being connected by bars *g*, and having lugs *h* arranged in the grooves of said guides *i*, substantially 85 as described.

JOHN HAMILTON.
